US0D1058554S

(12) **United States Design Patent** (10) Patent No.: **US D1,058,554 S**
(45) Date of Patent: ** Jan. 21, 2025

(54) **WEARABLE PERSONAL HEALTH,
ACTIVITY AND LIFESTYLE TRACKING
DEVICE**

(71) Applicant: **ULTRAHUMAN HEALTHCARE
PRIVATE LIMITED**, Bengaluru (IN)

(72) Inventors: **Apoory Shankar**, Bangalore (IN);
Yogansh Namdeo, Bengaluru (IN);
Anoop Jayan, Bangalore (IN)

(73) Assignee: **ULTRAHUMAN HEALTHCARE
PRIVATE LIMITED**, Bengaluru (IN)

(**) Term: **15 Years**

(21) Appl. No.: **29/850,626**

(22) Filed: **Aug. 22, 2022**

(30) **Foreign Application Priority Data**
